CONTROL MECHANISM

Robert J. Cinkutis, Croydon, and Stanley R. Kuczynski, Philadelphia, Pa., assignors to Philco-Ford Corporation, a corporation of Delaware

Filed Feb. 16, 1966, Ser. No. 527,940

8 Claims. (Cl. 74—10)

This invention relates to concentric shaft mechanism, and in particular to dual concentric shaft means for tuning and adjusting electrical apparatus such as radio receivers and the like. The invention has special reference to control arrangements in which one shaft is enclosed and journaled within another, for instance an inner tuning shaft within an outer sound control shaft.

In conventional apparatus the rotation of the outer shaft often disturbs the setting of the inner shaft, especially when the mechanism controlled by the inner shaft is a sensitive tuner which inherently imposes only a low torque load on its shaft. It is the main object of this invention to avoid such disturbance. A further object is to provide plural shaft apparatus which is simple, reliable, and easy to combine with associated devices.

Toward these objectives the invention provides a concentric shaft system wherein a first shaft, connectable to a low-torque load such as a tuner, has a brake advantageously engaged at all times and the action of which substantially increases the torque required to turn this shaft. This brake action prevents rotation of the low-torque shaft by other elements of the concentric shaft system and hence avoids the disturbance formerly caused by the turning of such other elements. In a preferred embodiment of our invention a brake drum is rigidly and coaxially secured to an inner and tuner-operating shaft. A pair of stationary brake shoes, one diametrically opposite the other, bear permanently against peripheral areas of the drum. Preferably the drum is also used as part of a coupling which connects the inner shaft with the tuner mechanism.

The invention will be understood more fully from the following description of the preferred embodiment thereof, incorporated in a radio tuner. In the drawing FIGURE 1 is a fragmentary plan view of the tuner, showing the new plural shaft system; FIGURE 2 is a generally similar view of the shaft system by itself; and FIGURE 3 is an exploded view of the new plural shaft apparatus. FIGURES 4 and 5 are, respectively, perspective views of the new tuning shaft and brake drum subassembly and of the brake shoe device cooperating therewith.

Referring first to FIGURE 1: the tuner 10 of a radio receiver is shown as having a knob 11 which drives an inner shaft in the new concentric shaft apparatus 12, said shaft driving a worm gear transmission 13 for the control of a core carriage 14 to shift magnetic cores 15 in the tuner. The shifting of cores, caused by the turning of knob 11, determines tuned characteristics of radio receiver circuits, not shown, which may for instance supply audio signals to a loudspeaker, not shown, forming part of said receiver.

The structure includes additional control means coaxial with tuning knob 11, for instance knob 16 for adjusting the volume of sound produced by the loudspeaker. This adjustment is effected with the aid of certain devices in the new shaft structure 12, as will be mentioned more fully hereinafter. Volume control knob 16 is fast on an outer shaft 17, wherein an inner shaft 18 is concentrically enclosed. Said inner shaft has one end connected to worm gear transmission 13 of the tuning mechanism, as will be described presently, while having an opposite end connected with an innermost shaft 19 which is rigid with tuning knob 11, as will be understood from FIGURES 1 to 3. The interconnection of shafts 18, 19 can be re-

2

leasable in order to facilitate removal of the knobs, as is well understood in the art.

According to the invention as fully illustrated in FIGURES 1 to 4, the new concentric shaft mechanism comprises a brake drum 20 rigidly secured to inner shaft 18 at the end thereof opposite tuning knob 11. As shown in FIGURES 1 and 5, a plurality of brake shoes 21, 22 are provided, uniformly bearing against this drum and symmetrically distributed about the same. Usually it is sufficient for purposes of our invention to provide a pair of brake shoes, one opposite the other, as is shown in the drawing. Brake drum 20 as shown in FIGURE 4 also provides, as a further and axially terminal portion thereof, a coupling element 30. This element, as shown in FIGURE 1, normally engages worm gear drive 13 of the tuner for driving the same.

The new brake shoes 21, 22, as best shown in FIGURE 5, are mounted on a stationary bearing structure 23 confined in a housing 23', while this housing, by a suitable extension thereof, supports shaft mechanism 12 on a rigid bracket 24 of tuner 10 (FIGURE 1). Each brake shoe is constructed in form of a small, elastic clip, held on this bearing structure 23, and each brake shoe has a free end arranged to bear against the side or peripheral surface of brake drum 20. Preferably the elastic clips or shoes are made of spring bronze or the like. In FIGURE 3 the clips are removed from support 23. They are shown as having mounting ends 25 embedded in a groove 26 which is formed in bearing unit 23 (FIGURE 5). This bearing unit, as well as brake drum 20 thereon, can comprise a body of synthetic plastic material. Brake drum 20 is coaxially riveted to inner shaft 18, see rivet element 27 in FIGURE 3.

The operation of the new apparatus is believed to be fairly obvious from the foregoing description of the structure. The user turns tuning knob 11, thereby rotating inner shaft 18 and brake drum 20 thereon (FIGURE 4). This drum, through coupling element 30, rotates worm gear transmission 13, which in turn shifts core carriage 14 and adjusts tuner 10 (FIGURE 1). By virtue of the new construction the adjustment of the tuner remains undisturbed once the proper tuning has been achieved. In particular this adjustment is not disturbed, as it formerly often was, by operation of volume adjusting knob 16 and outer shaft 17 thereon.

This latter shaft is shown (FIGURE 3) having a top end 17', normally secured to a conventional, rotatable potentiometer element 28 within housing 23', the potentiometer also having a stationary element 29 secured to stationary support 23. The stationary element 29 normally is in contact with rotor 28, and is connected with tuner 10 by suitable circuit means, not shown.

Heretofore trouble was often encountered with a tuner and the like when an outer shaft was rotated to adjust a potentiometer or the like. As one of these shafts was concentrically inserted in, and in surface contact with the other (as also shown in FIGURE 2), and was not held to any particular angular orientation, the rotation of the outer shaft tended to cause angular "creeping" or rotation of the inner shaft and thereby to disturb the delicate setting of the tuner. The trouble was particularly pronounced when a high gear ratio was provided in the gear mechanism, as is desirable for precise tuning.

The invention overcomes the trouble by the use of brake drum 20 on the shaft of tuning knob 11, FIGURE 4, in conjunction with brake shoes 21, 22 on bearing unit 23, FIGURE 5. The braking effect of these elements effectively overcomes the "creeping" tendency of the inner shaft and the consequent detuning effects. The new unit thus avoids the disturbance heretofore caused by interaction of outer and inner shaft surfaces. It avoids the kind of disturbance even if the torque load provided by tuner

10 and its gear drive 13 is very small. The improvement is achieved by the torque load which the brake imposes on tuning shaft 18.

As indicated in FIGURES 1, 4 and 5, the entire control apparatus, comprising brake unit 20, 21, 22 and bearing unit 23 for the same, is only about as large as a pair of control knobs 11, 16. It can be even smaller. The bearing unit, additionally containing potentiometer elements 28, 29 therein, is conveniently mounted on tuner bracket 24 by a rigid sleeve portion 31 extending from and coaxially to housing 23. A threaded end 32 of the sleeve extends through a suitable aperture in bracket 24, and is fastened to this bracket by nut 33.

It will further be seen that internal surface 34, FIGURE 3, is formed coaxially within the rigid sleeve for rotation of external surface 35 of outer shaft 17 therein, and that inner surface 36 of this shaft has a relatively wide front portion, separated from a relatively narrow rear portion by coaxial step 37. This step is engaged by a corresponding step 38 in outside surface 29 of inner shaft 18. All of these and the mating surface of inner shaft 18 are made as smooth as possible, and with suitable sliding fit. As will be clear from FIGURE 2, the inner shaft and brake unit is prevented from forward displacement (downward in the drawing) by the engagement of brake drum 20 with bearing unit 23, and is prevented from opposite or rearward displacement by bearing means 23 and by engagement between steps 37, 38. In similar way, outer shaft 17 is prevented from forward and rearward displacement by wall 40 of bearing unit 23 and potentiometer element 27, respectively.

It is preferred that the pressures applied by brake shoes 21, 22 to brake drum 20 be purely radial and symmetrical. No forces are then encountered—for instance at step 37, 38—which in any way cause significant interaction between the concentric shafts.

While only a single embodiment of the invention has been fully described, the details thereof are not to be construed as limitative of the invention. The invention contemplates such variations and modifications as come within the scope of the appended claims.

We claim:

1. In plural shaft mechanism for radio receivers and the like, wherein an inner shaft is journalled in an outer shaft for adjusting inherently low-torque mechanism, such as a tuner, by one of said shafts: a system for preventing

inadvertent turning of said shaft, comprising brake means and brake shoe means normally bearing against said brake means, one of said means being mounted on said shaft and rotatable therewith and the other being stationary with respect thereto.

5 2. Apparatus as described in claim 1 wherein said brake means is a drum mounted on said shaft, and said brake shoe means comprises stationary clip means bearing against a peripheral surface of said drum.

10 3. Apparatus as described in claim 1, wherein said brake shoe means comprises a plurality of brake shoes.

4. Apparatus as described in claim 1 wherein said brake shoe means comprises a plurality of brake shoes symmetrically distributed with respect to said brake means.

15 5. Apparatus as described in claim 4 wherein said brake means has a drum-shaped peripheral surface and said brake shoes bear radially against said peripheral surface.

6. Apparatus as described in claim 1, additionally including means for preventing axial motion of one of said shafts relative to the other.

7. Control mechanism for a radio receiver, comprising a tuner; inner and outer shafts, one of said shafts being arranged for setting said tuner, the other shaft having means mounted thereon for controlling the volume of the sound output of the receiver and said inner shaft being journalled in the outer shaft; and as means for preventing inadvertent turning of said one shaft, a brake drum rotatable with said shaft, and stationary brake shoe means permanently bearing against said drum, said shafts, brake drum, brake shoe means and means for controlling volume being in nested concentric relation.

30 8. Apparatus as described in claim 7 wherein said brake shoe means comprises stationary clips bearing against a peripheral surface of said drum.
